UNITED STATES PATENT OFFICE.

CARL F. EHINGER, OF CLEVELAND, OHIO.

ADJUSTABLE RADIATOR FAN.

Application filed November 14, 1924. Serial No. 749,983.

To all whom it may concern:

Be it known that I, CARL F. EHINGER, a citizen of the United States, and resident of Cleveland, in the county of Cuyahoga and 5 State of Ohio, have invented certain new and useful Improvements in Adjustable Radiator Fans, of which I hereby declare the following to be a full, clear, and exact description, such as will enable others skilled 10 in the art to which it appertains to make and use the same.

The objects of the invention are to provide an improvement in radiator fans for motor cars, and the peculiar novelty of the 15 invention lies in means for adjusting the angle of the blades of the fan to control the volume of cold air delivered to the engine, thus permitting the operator to provide the maximum amount of cold air to an over- 20 heated engine, and to vary the amount of air supplied thereto or to cut it off entirely as the outside temperature is reduced, thus enabling him to maintain the temperature of the engine as nearly constant as possible.

25 A further feature of great importance is found in the provision of means for reversing the angles of adjustment of the blades, thus enabling the operator to change the direction of the air current produced thereby, 20 the effect of which is to propel the heated air from underneath the hood in which the engine is enclosed, forwardly, through the radiator to heat the same, and to prevent the water therein from freezing and to draw 35 it out if it should become frozen.

The invention comprises a hollow hub in 40 which the blades are pivoted upon radial shafts—a stationary fan shaft, and a device movable in said shaft, and operatively connected with a rack member with which pinions upon said radial shafts engage,—to revolve all the blades simultaneously upon their radial axes. It also includes means accessible to the operator for manually controlling the operation of the device and for 45 limiting the amount of movement of said blades. It further includes guide means for giving a rectilinear movement to said rack member, which also serves to prevent the 50 revolution of said rack member in said hub.

The invention is hereinafter more fully described, illustrated in the accompanying drawings, and specifically pointed out in the claims.

55 In the accompanying drawings Fig. 1 is a side elevation of the device.

Fig. 2 is a longitudinal section showing a stationary shaft, a fan hub revolvable thereon, and blades mounted upon radial shafts which are pivoted in the hub, and a rack 60 member slidably movable in the hub upon the fan shaft, an inner operating rod or shaft, therefor, and guide means for said rack member,

Fig. 3 is a side elevation of the rigid or 65 stationary shaft, Fig. 4 is a perspective of the rack carrying sleeve or member, Fig. 5 is a perspective of one of the guides therefor, Fig. 6 is a side elevation of the complete device and Fig. 7 is a plan of the 70 positioning plate or temperature or guide for adjustment of temperature.

In these views A represents the stationary fan shaft rigidly secured to a bracket B, 75 secured to the motor frame,

C, is a hollow hub mounted upon the fan shaft and revolvable upon the shaft by means of the fan pulley,

D, attached rigidly thereto by means of 80 screws, D', D',

E, E, are fan blades mounted upon radial shafts F, F, which are provided with bearings, G, G, in the peripheral wall of the hub. F¹, are springs upon the radial shafts which 85 tend to keep the gears in mesh with the racks, and F² are external sleeves on these shafts for adjustment thereof, F³ are securing screws therefor.

Pinions H, H, are attached to the inner 90 ends of these shafts, and are engaged by racks I, I, tangentially secured to a member or sleeve J, which is slidably mounted upon the fan shaft and operated by mechanism as follows:

The preferred manner of accomplishing 95 this action is by means of a central rod K, which is slidably movable in the hollow fan shaft. Pins L, L, spaced apart in said rod project, through a longitudinal slot M in 100 said shaft and engage with washers L', L', which engage with opposite ends of said rack member or sleeve to move said rack member and rotate the pinions upon the radial blades upon the fan shafts. To prevent the rack member from rotating upon 105 the fan shaft, parallel guide bars N, N, are secured within the hub and the rack member travels upon these bars. The bars are secured by means of screws O, O, or other adjusting means which pass through the shell 110 of the hub, and lock nuts O', O', secure the screws from turning. The adjusting means

also permits the racks to be brought closer to the pinions to take up wear thereon and prevent noise.

5 Adjacent to the inner end of the rod K, are shown spaced recesses S, S, therein, in which a ball V is forced by a spring U, and a set screw T, at the several positions assumed by the rack to lock it therein, until moved therefrom by the driver. This screw 10 preferably passes through the lock nut W.

The rod K is operated from the driver's seat preferably by means of a bell crank P upon the bracket and a lever Q on the dash which moves over a graduated arc R, which 15 determines the exact position of the blades and their angular adjustment, to produce predetermined temperatures in the engine, and also indicates when the blades are reversed in position.

20 Having described the invention, what I claim as new and desire to secure by Letters Patent is:

1. In combination with a hollow stationary fan shaft and rigid support therefor, of 25 a hollow fan hub, and a pulley secured thereto and revolvable on said hollow shaft, fan blades and radial shafts therefor revolvable in the wall of said hub, pinions upon the inner ends of said radial shafts, a rack 30 carrying member slidable upon said fan shaft, and a rod longitudinally movable in said fan shaft, and means for engaging said rod with said rack carrying member.

2. In combination with a hollow stationary fan shaft and rigid support therefor of 35 a hollow fan hub, and a pulley secured thereto and revolvable on said hollow shaft, fan blades and radial shafts therefor revolvable in the wall of said hub, pinions upon 40 the inner ends of said radial shafts, a rack carrying member slidable upon said fan shaft, and a rod longitudinally movable in said fan shaft, means for engaging said rod with said rack carrying member, and 45 parallel guide means for said rack member in said hub.

3. In combination with a hollow stationary fan shaft and rigid support therefor of a 50 hollow fan hub, and a pulley secured thereto and revolvable on said hollow shaft, fan blades and radial shafts therefor revolvable in the wall of said hub, pinions upon the inner ends of said radial shafts, a rack carrying member slidable upon said fan shaft, 55 and a rod longitudinally movable in said fan shaft, means for engaging said rod with said rack carrying member, and parallel guide means for said rack member in said hub, and means for transversely adjusting said guide means.

4. In a device of the character described 60 in combination, a hollow hub, radially disposed shafts journalled therein, and fan blades secured thereon, pinions secured to the inner extremities of said shafts within

said hub, a stationary hollow fan shaft and support therefor, said hub being revolvable upon said stationary fan shaft, a rack carrying member slidably movable upon said stationary shaft within said hub, the racks 70 thereon engaging with said pinions upon said radially disposed shafts, a longitudinally movable rod in said hollow shaft and means upon said rod for engaging said rack carrying member. 75

5. In a device of the character described in combination, a hollow hub, radially disposed shafts journalled therein, and fan blades secured thereon, pinions secured to the inner extremities of said shafts within 80 said hub; a stationary hollow fan shaft and support therefor, said hub being revolvable upon said stationary fan shaft, a rack carrying member slidably movable upon said stationary shaft within said hub, the racks 85 thereon engaging with said pinions upon said radially disposed shafts, a longitudinally movable rod in said hollow shaft and means upon said rod for engaging said rack carrying member, said hollow shaft being 90 provided with a longitudinal slot through which said engaging means project.

6. In a device of the character described in combination, a hollow hub, radially disposed shafts journalled therein, and fan blades secured thereon, pinions secured to the inner extremities of said shafts within 95 said hub; a stationary hollow fan shaft and support therefor, said hub being revolvable upon said stationary fan shaft, a rack carrying member slidably movable upon said stationary shaft within said hub, the racks 100 thereon engaging with said pinions upon said radially disposed shafts, a longitudinally movable rod in said hollow shaft and means upon said rod for engaging said rack carrying member, said hollow shaft being provided with a longitudinal slot through 105 which said engaging means project, said racks projecting tangentially upon said 110 rack carrying member, and guide means for said racks within said hub, upon which said racks are slidably movable.

7. In a device of the character described in combination, a hollow hub, radially disposed shafts journalled therein, and fan blades secured thereon, pinions secured to the inner extremities of said shafts within 115 said hub, a stationary hollow fan shaft and support therefor, said hub being revolvable upon said stationary fan shaft, a rack carrying member slidably movable upon said stationary shaft within said hub, the racks 120 thereon engaging with said pinions upon said radially disposed shafts, a longitudinally movable rod in said hollow shaft and means upon said rod for engaging said rack carrying member, said hollow shaft being provided with a longitudinal slot through 125 which said engaging means project, 130

said racks projecting tangentially upon said rack carrying member, and guide means for said racks within said hub, upon which said racks are slidably movable, and means adjustable in the wall of said hub for supporting said guide means.

8. In a device of the character set forth, a fan shaft, a hollow hub revolvable thereon, radial shafts journalled therein, pinions secured to the inner ends thereof within said hub, a rack member slidably movable upon said shaft, said rack member being provided with tangentially disposed racks, and a sleeve body attached thereto and guide means for said rack member, said guide means serving also to prevent the revolution of said rack member upon said shaft.

9. In a device of the character set forth, a fan shaft, a hollow hub revolvable thereon, radial shafts journalled therein, pinions secured to the inner ends thereof within said hub, a rack member slidably movable upon said shaft, said rack member being provided with tangentially disposed racks, and a sleeve body attached thereto and guide means for said rack member, said guide means serving also to prevent the revolution of said rack member upon said shaft, said fan shaft being stationary and hollow, and means longitudinally movable in said shaft for operating said rack member.

10. In a device for rotating the blades of the radiator fan of a motor car, the combination with a stationary hollow shaft and a hollow fan hub rotatable thereon, of radial blades and shafts therefor journalled in said hub, pinions in said hub upon said radial shafts,—a rack carrying member sleeved over said shaft, the racks thereon being engaged with said pinions,—a rod reciprocable in said hollow shaft,—means for engaging said rod with said rack carrying member, and a positioning and operating means for said rod mounted upon the dash of said car.

11. In an adjustable radiator fan the combination with fan shaft, a hub revolvable thereon, radial blades and shafts therefor journalled in said hub, a rack carrying member slideable upon said shaft, and pinions on the inner ends of said shafts engageable with said racks, springs interposed between said pinions and the wall of said hub, and sleeves adjustably secured upon said shafts outside of said hub.

12. In an adjustable radiator fan for a motor car a hollow stationary fan shaft, a hub rotatable thereon, a multiple number of radial blades and shafts therefor journalled in said hub pinions upon the inner ends of said shafts, a rack carrier and racks therefor slidably mounted upon said shaft, a rod slidably movable in said shaft, means for operatively connecting said rod and rack carrier and spaced resilient locking means for said shaft.

13. In an adjustable radiator fan for a motor car a hollow stationary fan shaft, a hub rotatable thereon, a multiple number of radial blades and shafts therefor journalled in said hub pinions upon the inner ends of said shafts, a rack carrier and racks therefor slidably mounted upon said shaft, a rod slidably movable in said shaft, means for operatively connecting said rod and rack carrier and spaced resilient locking means for said shaft, and means positioned in the dash of said car for adjusting the position of said rod and rack carrier.

14. In an adjustable radiator fan, in combination, a stationary fan shaft, a hollow fan hub revolvable thereon, radial blades and shafts therefor journalled in said hub pinions on the inner ends of said radial shafts, a rack carrier slidably mounted on said fan shaft in said hub, an operating rod for said rack carrier, said rod slidably movable in said fan shaft, said fan shaft being longitudinally slotted, radial projections from said rod at opposite ends of said rack carrier, and annular washers between said projections and the ends of said carrier.

15. In a device of the character described, a fan hub, a stationary hollow shaft upon which said hub is rotatable, a support for the shaft, radial fan blades and shafts therefor, said shafts being revolvable in the walls of said hub, pinions on the inner ends of said shafts; a central operating rod passing through said shaft; a rack member longitudinally movable on said shaft and provided with racks engaging with the said pinions; means on said rod for engaging said rack member to reciprocate the same, said hollow shaft being provided with an opening permitting such engagement.

In testimony whereof, I hereunto set my hand this 18th day of October 1924.

CARL F. EHINGER.
